PACKAGE

Charles Weiner, Chicago, Ill., assignor to Chicago Printed String Co., Chicago, Ill., a corporation of Illinois

Application January 15, 1934, Serial No. 706,596

9 Claims. (Cl. 206—51)

The present invention relates to package and is herein described as a novel and convenient package for merchandising wrapped material, such as tying tape or the like, which package of merchandise is sold retail at low price.

The present invention has to do with a novel core so constructed as to prevent formation of creases in material wound about it and which core structure is economical to manufacture, is light in weight, and yet at the same time possesses adequate strength and rigidity for the purpose intended.

Heretofore it has been customary to package material such as tying tape or the like, as a package comprising a length of material wound about a flat core, such as cardboard. Such manner of winding has caused creases in the material where the same is bent about the edges of the core, and such creases are difficult, if not impossible, to eliminate. When such creased material has been utilized for use, and particularly tape utilized for tying packages, especially gift packages, the creases in the tape result in unsightly tied articles.

It is therefore an object of the present invention to provide a novel core of inexpensive material about which tape or similar material may be wound without the formation of creases.

Another object of the invention is to provide a core about which material may be wound for merchandising purposes, which core has arcuate ends to prevent creasing of material wound about it.

A still further object of the invention is to provide a novel, cheap, strong core for receiving wound material, so constructed as to prevent formation of creases in the material.

The above, other and further objects of the invention will be apparent from the following description, accompanying drawing, and appended claims.

The accompanying drawing illustrates embodiments of the present invention, together with the method of carrying out the same, and the views thereof are as follows:

Fig. 1 is a plan view of a wrapped package utilizing a core constructed in accordance with the principles of the present invention.

Fig. 2 is an end view of the core of Fig. 1, with the wound material omitted.

Fig. 3 is a longitudinal sectional view through Fig. 1, taken substantially in the plane indicated by the line III of Fig. 1.

Fig. 4 is a developed blank of which the core of Figs. 1, 2 and 3, is made.

Fig. 5 is a vertical sectional view through a core of modified form, and taken substantially in the plane indicated by the line V—V of Fig. 6.

Fig. 6 is a fragmental plan view of a core of modified form.

The drawing will now be explained.

The core utilized in the form of the invention illustrated in Figs. 1, 2 and 3 is fashioned from a blank of suitable material, such as cardboard, and is shown developed in Fig. 4.

The blank illustrated in Fig. 4 consists of a strip of cardboard having the ends cut to provide end extensions 1 and 2, with the side margins of the extensions notched at 3 and 4 respectively. Notches 5 and 6 are made in the side margins of the blank, midway of its ends, which notches are preferably slightly wider than the material to be wound about the completed core. Between the notches 5 and 6 and each end of the blank, longitudinal and transverse slits, 7 and 8 respectively, are made in the blank, to thereby provide longitudinally extending tangs 9 and 10. The slits 7 and 8 are so fashioned that when the blank is flat, the tangs 9 and 10, at any of the slits 7 and 8, extend toward each other.

To assemble the blank of Fig. 4 as a core, the blank is folded about the reduced portion formed by the slits 7 and 8, and the end extensions 1 and 2 brought together and suitably secured, as by glueing or pasting. The formation of the notches 3 and 4 adjacent the ends of the blank, cooperate to provide notches corresponding to the notches 5 and 6, and in register therewith, when the blank is looped as described. When the blank is looped, as just described, the tangs 9 and 10 extend outwardly at the ends of the loops, and constitute guides for the material wound about the core for preventing the material from slipping off of the core when so wound.

The material wound about such a core, herein illustrated as a tape A, is wound about the core as is customary, and then the free end of the tape is passed about the body of the core and surrounding the wound strands, and passes through the notches 5 and 6 with the free end of the tape passed through a bend 11 formed in the tape for passing it through the side notches, with the free end of the tape then secured to some convenient part of the core, as by a sticker 12. In applying the tape sidewise about the core and the wound strands, the central portion of the core is drawn together, as shown in Fig. 3 thus tending to hold the wound material safely in position on the core.

The modified form illustrated in Figs. 5 and 6 consists of a cardboard body 13 notched at its ends to provide guides 14 and 15 and also notched intermediate its ends to provide side notches 16 and 17. The end portions or parts of the core of this modification, are formed by cylindrical members 18 which are slotted at 19 and passed over the ends of the body 13 between the guides 14 and 15. The slotting of the cylindrical members 18 results in a tendency of these members to firmly grip the body 13 with sufficient engagement for all practical purposes. In this form of the invention, the tape is wound about the core as heretofore described and with the cross portion of the strand engaged through the notches 16 and 17 with its free end stuck to some convenient part of the core.

It will be observed that the core of the present invention may be made of inexpensive sheet material, without high labor cost, and may be quickly assembled for use. The provision of the arcuate end members of the body enables winding material about the core without forming creases in such material.

25 The end extensions 1 and 2 may be overlapped for completing the loop, in which event one of these extensions, for instance, the extension 1, may be provided with suitable adhesive. These extensions may also be connected together by 30 means of gummed strips applied to the abutting extensions 1 and 2 when formed into loop shape.

It will be observed that the core of the present invention lends itself very readily to economical manufacture on a production basis, and 35 is so constructed as to possess sufficient rigidity for the purpose intended. Furthermore it will be observed that the core prevents formation of creases in the material wound about it thus eliminating this objection to the present manner 40 of winding such material on flat cores.

It will be observed that the finished package of merchandise, wound in accordance with the principles of the present invention, possesses, in side elevation, the appearance of a figure 8.

45 The invention has been described herein more or less precisely as to details, yet it is to be understood that the invention is not to be limited thereby, as changes may be made in the arrangement and proportion of parts, and equivalents 50 may be substituted, without departing from the spirit and scope of the invention.

The invention is claimed as follows:

55 1. A winding core for tape and the like comprising a body fashioned from a strip of flexible material such as cardboard and the like with the free ends of the strip joined together forming a closed loop with arcuate ends and with the portions of the strip between the ends out of contact with each other and substantially 60 parallel, and said strip being longitudinally slotted adjacent the arcuate ends to provide guide tangs projecting beyond the ends with the planes of the said tangs coincident with the planes of the portions of the strip adjacent the ends.

65 2. A package of merchandise comprising a core and material wound about the core, said core consisting of a piece of strip material with the extremities joined together to provide a 70 looped body with arcuate ends, and with the portions of the strip between the ends out of contact with each other, the material being wound about said core over the arcuate ends and with the free end of the material passed cross-wise about the wound core and tightened 75

and fastened thereabout to draw together the central portion of the package into a shape in side elevation somewhat like a figure 8.

3. A package of merchandise comprising a core and material wound about the core, said core consisting of a piece of strip material with the extremities joined together to provide a looped body with arcuate ends and with the portions of the strip between the ends out of contact with each other, the material being wound about said core over the arcuate ends and with the free end of the material passed cross-wise about the wound core and tightened and fastened thereabout to draw together the central portion of the package into a shape in side elevation somewhat like a figure 8, and a plurality of flat tangs lying in the planes of the portions of the strip adjacent the ends and projecting beyond the arcuate ends serving as guides for the wound material. 20

4. A package of merchandise comprising a core and material wound about the core, said core consisting of a piece of strip material with the extremities thereof joined together to provide a looped body with arcuate ends and with the portions of the strip between the ends out of contact with each other, said portions between the ends being provided with registering marginal notches, the material being wound about said core over the arcuate ends and with the free 30 end of the material passed crosswise about the wound core within the registering notches and tightened to draw together the central portion of the package into a shape in side elevation somewhat like a figure 8. 35

5. A blank of flat material adapted to be fashioned in the form of a loop to provide a core for wound articles of merchandise, said blank being substantially in the form of a parallelogram with end portions of reduced width 40 projecting at each end of the blank adapted to be joined together to form the strip into a loop, the side margins of the blank being longitudinally and transversely slit to provide a plurality of pairs of longitudinally extending tangs, said slits being formed in the portions of the blank which constitutes the rounded arcuate ends of the core when the ends of the blank are together and the blank is in looped form so that said tangs project beyond the ends of the core as 50 guides for wound material. 45

6. A blank of flat material adapted to be fashioned in the form of a loop to provide a core for wound articles of merchandise, said blank being substantially in the form of a parallelogram with end portions of reduced width projecting at each end of the blank adapted to be joined together to form the loop and to provide side notches at the joint, said blank having notches in its side margins with one notch to a side and disposed opposite each other and disposed in the length of the blank to register with the notches formed by joining together said end portions, said blank being slit longitudinally 60 near each side thereof and between the notches and the ends of the blank, the blank also being slit inwardly from the side margins to the longitudinal slits to provide longitudinally extending tangs each side of every inward slit, said blank 70 being bent into loop form with the portions thereof between the opposed longitudinal slits forming arcuate ends and with the tangs projecting beyond the arcuate ends of the loop. 65

7. A package of merchandise comprising a 75

5 core and material wound thereabout, said core comprising a member having arcuate ends to prevent the formation of creases in the material wound about the same, said material being retained on said core by means about said material and crosswise of said package to draw together the material into a shape in side elevation somewhat like a figure 8.

10 8. A package of merchandise comprising a core and material wound about the core, said core consisting of a piece of strip material with extremities joined together to provide a looped body with arcuate ends and with the portions of the strip between the ends out of contact with each other, the material being wound around said core over the arcuate ends, and said material being retained on said core by means about said material and effective crosswise of the package to draw together the central portion of the package to draw together the central portion of the

15 package into a shape in side elevation somewhat like a figure 8.

9. A package of merchandise comprising a core and material wound about the core, said core consisting of a piece of strip material with extremities thereof joined together to provide a looped body with arcuate ends and with the portions of the strip between the ends out of contact with each other, said portions between the ends being provided with registering marginal notches, the material being wound about said core over the arcuate ends thereof, and said material being retained on said core by means within said notches and about said material and effective crosswise of the package to draw together the central portion of the package into a shape in side elevation somewhat like a figure 8.
